C. W. KUEN

RECEIVER SUPPORT FOR SOUND AMPLIFIERS

Filed May 1, 1922

UNITED STATES PATENT OFFICE.

CHARLES W. KUEN, OF CHICAGO, ILLINOIS.

RECEIVER SUPPORT FOR SOUND AMPLIFIERS.

Application filed May 1, 1922. Serial No. 557,663.

To all whom it may concern:

Be it known that I, CHARLES W. KUEN, a citizen of the United States, and a resident of Chicago, in the county of Cook and State 5 of Illinois, have invented a new and useful Improvement in Receiver Supports for Sound Amplifiers, of which the following is a full, clear, and exact description.

My invention relates to improvements in 10 receiver supports for sound amplifiers, and it consists in the combinations, constructions, and arrangements herein described and claimed.

An object of my invention is to provide a 15 device of the character described in which means is provided for yieldably holding telephone receivers, such as used in a radiophone receiving set, and directing the sound waves therefrom to the amplifying horn of 20 a phonograph or the like.

A further object of my invention is to provide a device of the character described which may quickly and easily be attached to 25 the ordinary type of phonograph amplifying horn in place of the ordinary type of phonograph reproducer.

A further object of my invention is to 30 provide a device of the character described which may be made of a single piece of stock, and which is relatively cheap to manufacture.

Other objects and advantages will appear 35 in the following specification, and the novel features of the invention will be particularly pointed out in the appended claims.

My invention is illustrated in the accompanying drawings forming part of this application, in which—

Figure 1 is a plan view of an embodiment 40 of my invention partially in section with one receiver in place, and

Figure 2 is a sectional view along the line 2—2 of Figure 1.

In carrying out my invention, I make use 45 of a Y-shaped tubular body member 1. The body member 1 and the remainder of the device, as hereinafter described, is composed of a partially vulcanized resilient rubber.

At each end of the shorter branches 2 and 50 3 of the body member 1 is provided an integral cup-shaped member 4. The members 4 are circular in shape and are centrally located upon the branches 2 and 3 of the body member 1. The bottom walls 5 of the members 4 are relatively thick, while the side 55 wall 6 are relatively thin, and may be easily

stretched. A rib 7 is provided at the outer edge of the members 4 for the purpose of reinforcing the side walls. The ribs 7 prevent the tearing of the side walls 6 as a telephone 60 receiver, as shown at 8, is inserted within the member 4. The inner surface of the walls 5 is provided with an annular outwardly extending ridge 9. The ridges 9 are concentric the mouths 10 of the branches 65 2 and 3 of the body member 1.

The larger of the three legs of the body member 1, as shown at 11, is provided with an annular rabbeted portion 12 on the inner walls thereof. The purpose of the rabbeted portion 12 is to admit the mouth of a tone amplifying horn 13 of the phonograph or the like. The rabbeted portion further prevents the mouth 13 of the horn from being placed too far into the body member 1. 75

From the foregoing description of the various parts of the device, the operation thereof may be readily understood. In using my receiver support, I first remove the mechanical reproducing mechanism from the phonograph tone arm and place the body member 1 so that the rabbeted portion 12 80 encompasses the mouth 13 of the tone arm.

I then place a telephone receiver 8, such as used in the ordinary type of radiophone receiving sets, in the cup-shaped member 4. This is done by manually stretching the resilient side walls 6 of the member 4 and slipping them over the cap 14 of the receiver 8. The side walls 6 are then released and they assume a position in close engagement with the caps 14, as shown in Figure 1, thus shutting out all outside noise and assuring the positive travel of the sound waves through the body member 1 and ultimately 90 into the mouth of the tone arm 13. The annular ridge 9 further acts as a means for confining the sound waves to the body member 1 inasmuch as the ridge 9 is at all times in close contact with the outer wall 15 of the receiver cap 14. 95

I then place a second receiver in the remaining member 4 and the device is ready for operation. When the radiophone set is in operation, the receivers 8 actuate to reproduce sound waves which travel from each of the receivers through the portions 2 and 3 of the member 1, and to the mouth of the tone arm 13. 105

I claim:

A device of the character described comprising a Y-shaped tubular sound conduct- 110

ing member constructed of resilient rubber, one branch of said Y-shaped member being tapered outwardly from the body portion thereof, and having a rabbeted portion on 5 the inner wall at the mouth of the branch, and integral cup-shaped supporting members carried by the remaining branches of

the tubular member at the outer ends thereof for yieldingly supporting a pair of telephone receivers, said cup-shaped portions 10 having their sound conducting passages arranged to register with the sound conducting passage in said telephone receivers.

CHARLES W. KUEN.
